HEEL

Giuseppe Filippelli, Brooklyn, N. Y.

Application January 5, 1934, Serial No. 705,319

5 Claims. (Cl. 36—42)

The present invention relates to heels, and more particularly to the type which is removable, replaceable or interchangeable.

The principal object of this invention is to provide novel and improved means whereby heels may be attached to shoes in such a manner as to be easily capable of being removed, replaced or interchanged by the wearer without the need of any special skill.

Another object of my present invention is to provide novel and improved means of the type described, whereby the heel of any shoe may be conveniently detached therefrom and attached to another shoe.

A further object hereof, is to provide a novel means of improved construction, whereby any single pair of shoes, as for instance, a pair of ladies' fancy pumps, may be fitted with any of many pairs of heels of different styles or designs as the occasion may dictate.

Another object is to provide novel and improved connecting means for facilitating secure mounting of the heel onto the shoe body.

Another object is to provide means of the class described, improved and novel in construction, which is cheap to manufacture, easy to use and efficient and well adapted for the purpose intended.

To attain these objects, in an embodiment of my present invention, I provide a slide member adapted to fit into and to be conveniently removable from a channel member. The former is provided with sidewise extending tongues, while the latter is provided with a series of correspondingly positioned yieldable sockets, into which the tongues set and become engaged; one of said members being secured to the shoe body, and the other being secured to the heel.

This invention is capable of numerous forms and various applications without departing from the essential features herein disclosed. It is therefore intended and desired that the embodiment shown herein be deemed illustrative and not restrictive, and that the patent shall cover whatever features of patentable novelty exist in the invention disclosed; reference being had to the appended claims rather than to the specific description herein to indicate the scope of the invention.

In the accompanying drawing, forming part of this application, similar characters of reference indicate corresponding parts in all the views.

Fig. 1 is a perspective view showing the slide member.

Fig. 2 is a similar view showing the channel member.

Fig. 3 is a perspective view showing the slide member mounted upon the heel seat of a shoe body.

Fig. 4 is a similar view showing the channel member mounted upon a heel which is to be detachably secured to the shoe body.

Fig. 5 is a section taken at line 5—5 in Fig. 3, but showing the heel secured to the shoe body 10 with the slide member within the channel member.

Fig. 6 is a section taken at line 6—6 in Fig. 2.

In the drawing, the numeral 10 designates generally a slide member which is adapted to receive 15 thereon a channel member which is generally designated by the numeral 11.

The slide member 10, preferably of sheet metal, consists of a substantially elongated trapezoidal plate portion 12, pointed at its narrower end 13, 20 having pairs of sidewise extending tongues 14 and 15 and provided with opposite pairs of perpendicularly extending spacer elements 16, which terminate in nail portions 17. This member 10, is secured to the shoe body 18, at the exterior heel 25 region called the heel seat thereof, with point 13 towards the heel end of the shoe body 18. In the construction shown, the spacer elements are cut in and bent up to leave the marginal flange portions 19.

The channel member 11, also of sheet metal, is shaped to admit the plate portion 12 within its up-and-in turned ends, in particular, the channel segments 20, which receive the flange portions 19, and the segment 21 for the admission 35 of the pointed end 13, while in the yieldable and resilient sidewise extending sockets 22 and 23, snap the tongues 14 and 15, serving thereby to lock the member 10 within the member 11, whereby the heel 24, onto which the member 11 40 is secured within the recess 25, becomes attached to the shoe body 18.

With not too much force, the heel 24, can be readily detached by sliding it away from the toe end of the shoe body 18, for upon so doing, the 45 tongues 14 and 15, will free themselves from the grip of the sockets 22 and 23 respectively.

In the manner above set forth, any number of heels of different design and character, each having mounted thereon a member 11, can be 50 chosen from, to be easily attached and detached to and from a shoe body fitted with a member 10.

To secure this member 10, referring to Fig. 5, the nail portions 17 thereof are driven through the shoe body outer component 26, and through 55

- its inner lining 27, over which the pointed projecting ends of said nail portions 17, are bent; an inner sole member 28, covering the exposed ends of said nails. The bodies of both members 5 10 and 11, are curved concave a little to give them greater springiness and to conform to the concavity of the heel top surface made necessary in order that the heel's upper edge 29, make perfect contact with the shoe body 18.
- 10 It is to be noted that the socket segments 22 and 23, are independent of the channel segments 20, to give the former greater elasticity, which condition is further enhanced by the slits 30. Also note, that the leather tongue 31, in being 15 pasted over the breast surface of the heel 24, serves to hide the members 10 and 11, by closing their compartment in the combination set forth.

Having described my invention, I claim:—

1. In combination, a shoe body, a heel body, 20 a slide member secured to one of said bodies and provided with a sidewise extending tongue, and a channel member within which the slide member is positioned, secured to the other of said bodies; said channel member being provided with a sidewise extending yieldable socket 25 within which the slide member tongue fits.
2. In combination, a shoe body, a slide member secured to the shoe body at its external heel region and spaced therefrom, said slide member 30 being provided with tongues on either side thereof extending towards the side of the shoe body, a heel, and a channel member within which the slide member is positioned, secured onto the heel; said channel member being provided with yield- 35 able sockets extending towards each side of the

heel, within which the slide member tongues fit.

3. In a shoe heel attachment structure of the class described, a slide member comprising a sheet body, having formed therefrom, opposite pairs of perpendicularly extending spacer components, each terminating in nail portions; said body being provided with sidewise extending tongues, and a channel member within which the slide member is positioned, comprising a sheet body having its side ends in segments bent over 10 upon themselves forming a pair of charniel components wherein the slide member rests as aforesaid, and a pair of yieldable sockets within which the slide member tongues fit; one of said members being adapted to be mounted upon the heel 15 rest of a shoe body, and the other of said members being adapted to be secured upon a heel.

4. In a shoe heel attachment structure of the class described, a slide member comprising a trapezoidal sheet body having spacer elements 20 extending perpendicularly from one face thereof, and sidewise extending tongue portions near each vertex thereof, and a channel member within which the slide member is positioned, comprising a similar shaped body sheet portion having 25 sidewise extending yieldable socket elements near each of its vertices within which the slide member tongues fit, and a pair of channel segments intermediate said socket elements wherein the slide member rests as aforesaid; one of said members being adapted to be mounted upon a heel 30 and the other upon the heel rest of a shoe body.

5. In a structure as in claim 4, wherein the bodies of the members are bent concave.

GIUSEPPE FILIPPELLI.
